(57) **CLAIM**

The ornamental design for an apparatus holder, as shown and described.

DESCRIPTION

FIG. 1 is a perspective view of an apparatus holder;
FIG. 2 is a front view of the apparatus holder shown in FIG. 1,
FIG. 3 is a right end view of the apparatus holder shown in FIG. 2,

FIG. 4 is a left end view of the apparatus holder shown in FIG. 2,
FIG. 5 is a top view of the apparatus holder shown in FIG. 2,
FIG. 6 is a bottom view of the apparatus holder shown in FIG. 2; and,

FIG. 7 is a rear view of the apparatus holder as shown in FIG. 2.

The broken lines shown in the drawings represent portions of the apparatus holder that form no part of the claimed design. The apparatus holder is used for supporting for example An electronic tablet on a support device. The lower part is adjustably extendable to adapt its position to the size of the apparatus and is lockable in the selected position. The upper part is spring-biased inwardly to engage an apparatus received between the lower and the upper part. At its rear the holder is provided with mounting means for attachment to a support device.
